UNITED STATES PATENT OFFICE

RONALD GEORGE GRIFFITH, OF CROYDON, ENGLAND, ASSIGNOR TO CREED AND COMPANY, LIMITED, OF CROYDON, ENGLAND

PRINTING TELEGRAPH RECEIVING APPARATUS HAVING CASE GROUPING OF CHARACTERS

Application filed February 29, 1932, Serial No. 595,852, and in Great Britain November 27, 1931.

This invention relates to telegraph printing apparatus operating according to a code in which particular code signal combinations are employed as case signals to differentiate between different characters corresponding to identical signal combinations in different case groups.

As the possible number of permutations of a given number of signal elements is limited, it is usual when a number of selections is required in excess of the maximum possible with any particular code, to extend this number by preceding each signal combination or group of signal combinations by a case identifying signal, which may operate a platen or type case shift in a printing apparatus. For most telegraphic purposes this method has been found sufficient to provide the number of selections required. For certain purposes, however, a still further number of possible selections is required. This occurs, for instance, where it is desired to adapt telegraph printing apparatus for communicating intelligence in such as certain oriental or other languages wherein selection is required from a large number of characters.

In this connection it is to be understood that although for simplicity in the following description the selection of one of a plurality of printing characters may be referred to, this is intended also to include the selection of one of a number of printer functions such as line and page feed which are usually selected and controlled in a similar manner to the printing characters.

It is possible to obtain any required number of selections without case signals by increasing the number of units or elements in each signal combination. This has the disadvantage of increasing the line time required for the transmission of each signal combination. It may be stated therefore that a five unit code together with case signals has satisfied most normal requirements, and apparatus for operating according to this code has been well tried and widely exploited.

The object of the present invention is to provide telegraph printing apparatus op-

erating on a code having a similarly limited number of signal units and in which a greater number of selections is provided than by a single alternative case group of characters, and for this purpose utilizes the principle of grouping of allied selectable characters in order of frequency of usage.

According to the invention, therefore, a printing telegraph receiving apparatus comprises a printing telegraph receiving apparatus comprising a series of permutation members operable in accordance with the permutation elements of a signal combination, a first case shift mechanism operable in response to particular settings of said series of permutation members for controlling selection in one or another of two case groups each group having two selectable characters or operations for each selection effected therein by said permutation members, and a second case shift mechanism operable in response to further particular case signals controlled through said series of permutation members for effecting selection from one or the other of each two said selectable characters or operations.

In a preferred embodiment of the invention a printing telegraph receiving apparatus comprises a series of permutation members operable in accordance with the permutation elements of a signal combination, a further permutation member operable in response to particular settings of said series of permutation members, a plurality of selectable members operable in accordance with the setting of all of the permutation members and a case shift mechanism operable in response to the selection of one or another of two selectable members for selecting one or the other of two characters corresponding to each of said plurality of selectable members.

Although, to select certain characters by this means, two successive case signals are required and each of the means responsive to each case signal respectively may be considered as a case shift mechanism, the method according to the invention as above set forth is particularly advantageous as the provision of a further permutation member

operable in response to a case signal received by a particular setting of a series of similar notched members, although a species of case shift mechanism which is already known is 5 in reality a means whereby the selection of any one of a larger number of selectable members can be effected as in the instance where another unit is added to a signal code, in contradistinction to the more usual 10 form of case shift mechanism thereafter referred to which may consist of the actuation of a platen from one to the other of two positions or alternatively the corresponding actuation of a type basket or type 15 wheel.

In signal transmitting apparatus by which printing apparatus according to the invention may be controlled the various case signals may be transmitted under the control 20 of separate key levers in the keyboard, but the invention is of particular value when used in conjunction with a keyboard controlled signal transmitting apparatus according to my copending application Ser. 25 No. 595,851, filed February 29, 1932, in which apparatus the first case signals are automatically inserted in the transmitted signals when a key is operated in a change of case.

30 In the single figure of the accompanying drawing a perspective view is shown of a preferred selecting mechanism together with those portions of a printing apparatus which it is considered necessary to be shown 35 for the comprehension of the construction and mode of operation of an example according to the present invention.

The armature 1 of a signal receiving relay (not shown) actuates latch members 2 and 40 interposable member 3 in response to the character of received signal elements. Latch members 2 on each actuation release a clutch 4 for a predetermined degree of rotation, in this instance for half a revolution, in a manner already well-known. Clutch 4 effects 45 the rotation of a cam sleeve 5 from a continuously rotatable driving shaft 6, which is driven by means (not shown) at a speed determined by that of the received signal elements. Cam sleeve 5 carries a cam 7 adapted 50 to oscillate a hammer 8 in the axial direction of the sleeve 5 in the cadence of the elements of received signals. Also carried on cam sleeve 5 and fixed thereto are two discs 9 and 55 10 which in turn carry a series of rods 11 circularly arranged around the shaft and axially movable in suitable holes in the discs 9 and 10. As the present arrangement is intended for operation according to a five unit 60 code and as clutch 4 is arranged to rotate a half revolution at each release there are ten of these rods 11, each pair of rods on opposite sides of a diameter of the shaft being fixed to one of a series of five cam members 65 12 to 16 slidably axially on sleeve 5 but ro-

tatable therewith. Cam 7 is set relatively to rods 11 so that hammer 8 is actuated towards each rod to effect a striking movement during the interval in which each successive rod moves past a position opposite the hammer tip. The interposable member 3 is actuated by armature 1 either to a position between hammer 8 and the path of movement of the tips of the rods so as to effect the movement of a rod by the hammer, or to a position where movement is not conveyed from the hammer to a rod. As interposable member 3 is on an arm pivoted at 17, it will be seen that it does not impede the striking movement of hammer 8, but transfers the movement of the hammer to the appropriate rod only when interposed therebetween. Each of the five cam members 12 to 16 for each received signal combination are thus set in one or the other of two axial positions 70 on cam sleeve 5, in accordance with the character of the corresponding signal elements. In order to prevent any undesired movement of the rods, spring means, such as indicated by 18 in the drawing, may be provided to 75 press on one or the other side of a raised cam surface 19 on each rod to tend to hold the rod in whichever position it is located.

Each of the cam members 12 to 16 has two cam fingers or projections 20, 21, arranged 80 on opposite sides of a diameter, each of the series of projections being in line along the shaft. On either side of the shaft and co-operating with the cam projections are two series of corresponding vertical levers 22 and 23 pivoted on horizontal rods 24 and 25 respectively, one series of levers being located in a displaced position in the axial direction of the shaft relatively to the other series of levers, so that when all of the cam members 12 to 16 have been set in accordance with the elements of a received signal and preferably just before the cam sleeve 5 is re-arrested on termination of the signal, the double series of cam projections 20 and 21 rotate past the vertical levers and positively actuate one or the other of each pair of levers according to the one or other axial position to which each cam member has been set. A resetting bar 26 bearing a series of 90 cam surfaces 27 is arranged to engage with any actuated cam member and reset it to the unactuated position on the sleeve at any convenient period during the rotation of the shaft before each cam reaches the position 95 to be actuated if selected in the next signal combination.

The upper extremities of each pair of vertical rods 22 and 23 are located between the sides of an actuating notch 28 of a corresponding permutation member of which in the present case there are five, 29 to 33, corresponding to the five pairs of rods and the five permutation elements of a signal combination. When therefore one or the other of 100

each pair of vertical levers 22 and 23 is actuated by its associated cam member 12 to 16, the corresponding permutation bar is positively actuated to one or the other of two longitudinal positions. These permutation bars co-operate with a plurality of transversely arranged selector members as indicated by members 34 to 37 for instance, but of which usually there are as many as there are permissible permutations of the settings of the series of permutation bars 29 to 33, as already well-known. It may here be remarked, however that for the purposes of the present invention, there is a larger number in this series of selectable members than can be provided for by the series of five members 29 to 33 only, as will hereinafter appear. In the present instance the permutation bars are shown with square cut code notches 38 which permit one of the series of transverse members to drop when an aligned series of notches is formed, and a universal bar 39 actuated through the release of a clutch 40 when released by latch 41 which latch is conveniently actuated by a cam 42 on disc 10 rotating with sleeve 5. The clutch 40 is conveniently driven from continuously rotating shaft 6 from skew gears 43, 43' as shown.

The two transverse members 34 and 35 shown in the drawing are only in operative relation with the five permutation bars 29 to 33 and are selected by the particular setting of these bars in response to a received case shift or re-shift signal respectively. In the arrangement according to the present invention instead of these two bars controlling a platen or type basket shift for change of case a further notched bar 44 is actuated to one or the other of two positions through a three-armed bell crank lever 45 pivoted at 46. This bar 44 co-operates with the series of other bars 29 to 33 and now, in effect, makes the selection of any one of the plurality of other selectable members as 36 and 37 depend upon the setting of a series of six instead of five permutation members. Therefore the number of selectable members may be increased to the maximum number of permutations afforded by the series of six bars instead of five. This, as is well-known, is practically double that of the maximum number afforded by the five bars alone, and the selecting mechanism described may therefore now be considered as a six unit selecting mechanism, but of which five permutation bars are set in accordance with a five-unit code and the sixth bar is set in accordance with particular settings of the said five members responsive to particular case signals. All of the selecting members with the exception of the two case selecting bars 34 and 35 may be as previously mentioned, under the control of the sixth permutation bar. With the exception of those

members reserved for certain printer functions, such as line and page feed and further case signals for instance, each member may be utilized to control a corresponding type bar or the particular degree of rotation of a type wheel as already known, and therefore the mechanism of which is not further shown.

As already intimated, the particular method of actuating a further permutation bar in response to a case signal may be considered to be already known in the art, but it has an important advantage for the purpose of the present invention in that a further case shift by moving a platen or type basket can now be effected, for providing a still further series of possible selections of printing characters. In the arrangement shown in the drawing this is effected under the control of two selectable members 36 and 37, each of which may be selected by particular settings of the first five members 29 to 33 only or preferably of all the six notched bars.

If bar 37 for instance is selected by falling into an aligned series of notches in the permutation bars, on actuation of universal bar 39 the bar 37 is moved longitudinally and a shoulder 47 on the bar engages a bell crank lever 48 which raises a lever 49 pivoted at 50 and on which lever 49 the end of a rotatable platen 51 is shown supported at the free extremity. Bell crank lever 48 is preferably fixed to a rock shaft which is extended to the opposite end of the rotatable platen, and raises a lever corresponding to lever 49 through another bell crank lever corresponding to lever 48. When actuated to the raised position latch member 52 engages a fixed stop member 53 and maintains the platen in this position until a re-shift signal is received when selector bar 36 is actuated longitudinally by the universal bar 39 to effect the engagement of a shoulder 54 on bar 36 with the end of latch member 52 to disengage it from the fixed stop 53 and permit the platen to resume its original position.

It will be understood that for the movement of a platen in this manner to effect a change of case each of the plurality of selectable members selects two printing characters the printing of one of each pair of selected characters being effected in the one or other position of the platen. If the selectable members each control the degree of rotation of a type wheel two corresponding series of printing characters are provided on the type wheel and the movement of the platen is effected from one to the other of each pair of characters in the selected position. Alternatively the platen may remain stationary for the second case shift and the actuation of bell crank lever 48 may effect the movement of a type basket or type wheel to bring the

one or other of two selectable printing characters to the printing position.

What is claimed is:

1. A printing telegraph receiving apparatus comprising a series of permutation members operable in accordance with the permutation elements of a signal combination, two case groups, a first case shift mechanism operable in response to particular settings of said series of permutation members for controlling selection in one or another of two case groups, each group having two selectable characters or operations for each selection effected therein by said 10 permutation members, and a second case shift mechanism operable in response to further particular case signals controlled through said series of permutation members for effecting selection from one or the 20 other of each two selectable characters or operations.
2. A printing telegraph receiving apparatus comprising a series of permutation members operable in accordance with the 25 elements of each signal combination, a further permutation member operable in response to particular settings of said series of permutation members, a plurality of selectable members operable in accordance 30 with the settings of all of said permutation members, two additional selectable members each operable in accordance with particular settings of all of said permutation members, and a case shift mechanism operable 35 in response to the selection of one or another of said two additional selectable members for selecting one or the other of two characters corresponding to each of said plurality of selectable members.
3. A printing telegraph receiving apparatus for type selecting operations under control of five unit code signal combinations characterized by the use of six permutation members five of which are positioned in accordance 45 with received signal elements, means responsive to particular settings of the other five permutation members to position the sixth permutation member, case shift mechanism for moving a platen or type basket, means responsive to particular settings of the said six permutation members to operate the case shift mechanism.
4. A printing telegraph receiving apparatus comprising a series of six permutation members five being operable in accordance 55 with the elements of each signal combination, two transversely arranged members each selectable in accordance with one of two particular settings respectively of said five permutation members, a pivoted lever having two arms extending on either side of the pivotal point and engaged by said two transversely arranged members respectively 60 of the pivotal point and engaged by said two transversely arranged members respectively

to move the sixth said permutation member from one to the other of two positions, a plurality of selectable members operable in accordance with the settings of said series of permutation members, two additional 70 selectable members each operable in accordance with particular settings of said series of permutation members, and a case shift mechanism operable in response to the selection of one or another of said two additional 75 selectable members for selecting one or the other of two characters corresponding to each of said plurality of selectable members.

5. A printing telegraph receiving apparatus comprising a series of permutation members operable in accordance with the elements of each signal combination, a further permutation member operable in response to particular settings of said series 80 of members, a plurality of selectable members operable in accordance with the settings of all of said permutation members, a lever moved to one position on actuation of a member selectively controlled through 85 said series of permutation members, latch means to retain said lever in the actuated position and operable under control of a further selectable member to unlatch said lever, and a case shift mechanism moved by 90 said lever for selecting one or the other of two characters corresponding to each of said plurality of members.

6. A printing telegraph receiving apparatus comprising a series of six permutation members five being operable in accordance 100 with the elements of each signal combination, two transversely arranged members each selectable in accordance with one of two particular settings respectively of said five permutation members, a pivoted lever having two arms extending on either side of the pivotal point and engaged by 105 said two transversely arranged members respectively to move the sixth said permutation member from one to the other of two positions, a plurality of selectable members operable in accordance with the settings of said series of permutation members, two additional 110 selectable members each operable in accordance with particular settings of said series of permutation members, a lever moved to one position on actuation of one of said two additional selectable members, latch means to retain said lever in 115 the actuated position and operable under control of the other of said two additional selectable members to unlatch said lever, and a case shift mechanism moved by said lever for selecting one or the other of two characters corresponding to each of said 120 plurality of selectable members.

RONALD GEORGE GRIFFITH.
